UNITED STATES PATENT OFFICE.

WALTER C. POWELL, OF COLUMBUS, OHIO.

SEALING-TAPE MOISTENER.

1,311,007.

Specification of Letters Patent. Patented July 22, 1919.

Application filed February 12, 1919. Serial No. 276,569.

To all whom it may concern:

Be it known that I, WALTER C. POWELL, a citizen of the United States of America, residing at Columbus, in the county of Franklin and State of Ohio, have invented new and useful Improvements in Sealing-Tape Moisteners, of which the following is a specification.

The purpose of the invention is to provide a device or apparatus for supplying strips of paper, cloth or the like for wrapping or binding packages, for use as labels or for other kindred uses. To this end the invention comprises a base frame, a suitable paper holding device or reel on which rolls of gummed paper may be supported, a water pan or reservoir, a roll mounted in the frame for rotary movement therein so that it may be moistened by contact with the water in the pan, and suitable guiding means by which the strips of paper uncoiled from the rolls may be brought into contact with the last said roll for the purpose of moistening the gummed surface of the strip so that it may be in condition for attachment to a package immediately upon its withdrawal from the machine. Means is also provided for varying the width of the guides through which the paper passes to the moistening roll or member and such a means provides for the employment of different widths of paper rolls carried on the reel or one roll at full width of the reel on the machine.

The invention is illustrated and described in a specific embodiment to which, however, it is not to be restricted. The right is reserved to make such changes or alterations, as the actual reduction to practice may suggest, in so far as such changes or alterations are compatible in spirit with the annexed claims.

The same numerals of reference designate the same parts throughout the several figures in the drawings, wherein:

Fig. 1 is a view in side elevation of the improved machine.

Fig. 2 is a top plan view.

Fig. 3 is a longitudinal sectional view taken on the line 3—3 of Fig. 2.

Fig. 4 is a transverse sectional view taken on the line 4—4 of Fig. 2.

Fig. 5 is a plan view of one of the division plates carried by the reel.

Fig. 6 is a section on the line 6—6 of Fig. 5.

Fig. 7 is a plan view showing in folded po-

sition the division plates illustrated in Fig. 5.

As shown, the invention comprises a base or frame A. This frame is of an open character and is formed with two longitudinal side plates 1 which connect with a front transversely disposed plate 2. The side plates 1 are further connected by a second transversely disposed plate 3 and at the bottom edge of this plate 3 and the adjacent edges of the plates 1 there are formed webs 4 which are provided with holes 5 through which there may be passed screws for the purpose of securing the base or frame A on top of a shelf, counter or the like. Adjacent the juncture of the front plates 2 and the side plates there are formed webs 6 similarly provided with holes through which screws may be passed for the similar purpose of securing the frame to a counter, shelf or the like.

Attached on the upper edges of said plates 1 and extending from the cross plate 3 to within a specified distance of the front plate 4, there is a plate 7. This plate spans the same and is secured in place by means of screws 8 which enter tapped holes in the upper edges of the plates 1. This plate 7 extends over the cross plate 3 and this extending portion is curved downwardly as indicated at 9. The screws 8 adjacent the plate 3 serve also to secure to the frame a narrow plate 10, this narrow plate being spaced above the plate 7, narrow strips 11 being interposed between it and the plate 7 for the purpose of effecting this spacing. The screws 8 also pass through the strips 11. The plate 10 at that edge adjacent the curved edge 9 of the plate 7 is curved upwardly as indicated at 12. There is thus provided a flaring mouth through which the gummed paper or sealing strips may be passed from the reel, later described, to the moistening roll. Mounted at that end of the plate 7 remote from the end 9, there is a narrow transversely disposed plate 13, this plate being mounted on top of the strips 11 and being secured in place on the frame by the screws 8 which secure the plate 7 to the frame at this end. Plate 13 is thus spaced above the plate 7 as is the plate 10 and this plate is beveled to provide a cutting edge 14 which cutting edge is divided up into a series of teeth by means of slits 15.

Mounted adjacent the front plate 2 but so supported that it may rotate, there is a

moistening roll 16 which is of collar construction and which is formed with a plurality of perforations 17 distributed over the whole of its cylindrical surface. This moistening roll or drum 16 is provided with trunnions 18 at its ends and these trunnions rest in suitable bearings formed in the side plates 1 adjacent the front plate 2. The roll 16 is mounted so that it may be easily removed from the frame and to this end the side plates are formed with the recesses 21 extending from the bearings for the trunnions 18 to the upper edges of the plates. Thus while gravity keeps the trunnions 18 of the roll in their bearings, the roll may be easily removed simply by raising it out of the frame.

A pan 19 is carried within the frame directly below the roll 16 and this pan rests upon interned lugs 20 formed with the side plates 1 at the bottom edges thereof, the webs 6 serving as further supports for this pan. In order that the pan may be easily removed after the roll has been removed, a recess 21 is formed in the front plate 2 so that a finger grip may be easily had on the front wall of the pan to permit the ready removal thereof.

Bolted at the rear end of the frame A—that is, the end remote from the roll 16—there are two narrow upright plates 22, one on each side of the frame. A pintle 23 is supported by these plates and this pintle receives on its opposite ends the knurled or milled nuts 24 which abut the plates to hold the pintle in place. This pintle is designed to support the several rolls of sealing tape 25, which, if there are more than one, are separated by appropriate division plates comprising the plates 26 and 27 which are pivotally connected together by a pin or rivet 28. When these division plates are in use their giving the relative positions shown in Fig. 5 when the eyes 29 and 30 in each of the two plates are brought into registration and the pintle may be passed through either pair of these registering eyes to mount the plates on the pintle. The plates 22 are also provided with two eyes through which the pintle may pass, the upper eyes 31 being obviously for the purpose of receiving the pintle when larger rolls of tape are used than those shown at present in the drawings. Thus when certain size rolls are employed the pintle is placed in the lower eyes of the plates 22 and when larger rolls are employed the pintle is placed in the upper eyes 31, thereby providing for the rotation of rolls of greater diameter than those usually employed. The division plates are loosely mounted on the pintle between adjacent rolls and when the smaller rolls are used the pintle passes through the eyes 29 of the division plate and when the larger rolls the pintle is passed through the eyes 30.

When the device is not in use and it is desired to dismantle the same for shipment or storage, the pivot studs or rivets 28 provide means for folding the division plates so that the plates 26 and 27 are brought into alignment with each other, as shown in Fig. 7, when the folded parts obviously require less room than when in the extended position shown in Fig. 5.

In leading the tape 25 from the reel to the moistening roll, it is passed under the plates 10 and 13 but on top of the plate 7 and the free ends passing out beside the cutting edge 14, are carried over the upper surface of the roll 16. It will be observed that the device herein shown is carrying three different widths of tape and in order that the separate pieces may be guided to the moistening roll and kept out of contact with or entanglement with each other, suitable guiding means are provided and these guiding means comprise screws 32 which threadingly engage tapped holes formed at intervals through bolted plates 10 and 13. The spacing of the holes is such that this variation in width between adjacent screws may be obtained to suit any variation in width of the different rolls of the tape that may be carried on the reel and the screws having been once positioned for a certain width of the tape, the tape passes between adjacent screws and in this way is led to a definite place on the moistening rolls 16.

The use of the device is obvious. The rolls of tape 25 revolve loosely on the pintle 23 and when it is desired to draw off a certain length of any desired width of tape, the tape having the desired width is drawn out over the roll 16, the latter being rotated by this operation, and being in contact with the water in the pan 19, picks up the water and thus moistens the gummed side of the tape which contacts with it. The required length of tape having been withdrawn, the edge 14 provides means for shearing the tape off at this point, when the tape is then ready for attachment to a bundle or package.

The invention having been described, what is claimed as new and useful is:

1. In a sealing tape moistener, an open frame, a reel mounted at one end of the frame, a moistening roll rotatably mounted at the opposite end of the frame, a plate positioned on top of the frame between the reel and the moistening roll, other plates mounted on top of the first said plate at opposite ends of the latter and spaced above the same, a moistener pan carried within the frame with whose contents the moistening roll is brought into contact, means for guiding strips carried by the reel and passed between the first and second said plates to the moistening roll, and means for severing the strips adjacent the roll, whereby no part of the strip which has been brought into

contact with the roll will remain unsevered. 2. In a sealing tape moistener, an open frame, a reel mounted at one end of the frame, rolls of tape carried by said reel, a 5 plate disposed transversely across the frame, a second plate mounted on top of the first plate but spaced above the latter and standing adjacent one edge thereof, a third plate also mounted on top of the first said 10 plate but spaced above therefrom, the last said plate standing adjacent the opposite edge of the first said plate and having a cutting edge formed thereon, a moistening roll rotatably mounted in the frame at the 15 end opposite the reel, a moistener pan with

whose contents the moistening roll contacts, the second and third said plates being formed with a plurality of spaced tapped holes, and screws engaged in certain of said holes, the screws being adapted for attachment in different holes to vary the spaces between adjacent screws, the tape from the rolls on the reel passing above the first said plate and below the second and third said plates to the moistening roll and between adjacent 20 screws in the second and third said plates, whereby the tape is guided to the moistening rolls in the manner herein specified. 25

In testimony whereof I affix my signature.
WALTER C. POWELL.
